UNITED STATES PATENT OFFICE.

ORLO L. WOOD, OF LANSING, MICHIGAN.

GAGE.

1,317,061.

Specification of Letters Patent. Patented Sept. 23, 1919.

Application filed May 9, 1919. Serial No. 295,845.

To all whom it may concern:

Be it known that I, ORLO L. WOOD, a citizen of the United States, residing at Lansing, in the county of Ingham and State of Michigan, have invented new and useful Improvements in Gages, of which the following is a specification.

This invention relates to improvements in printing presses and particularly to means for the automatic feeding of such presses, the object being to improve the feeder now used on presses of the Gordon type.

To this end the invention contemplates the provision of an improved finger, which is actuated in the usual manner to remove the paper to its final position against the gage pins after having been automatically delivered to the platen.

In the form of the finger now used and with the Miller automatic feeder for Gordon presses, it is necessary to provide different fingers for feeding paper of different thicknesses, the finger used for feeding paper of ordinary thickness not being adapted for feeding heavy paper or cardboard.

The invention aims to provide a finger which may be substituted for the one now in use and which will feed the material of all thicknesses from tissue paper to cardboard, thereby avoiding the necessity of providing extra fingers and the consequent loss of time for changing them.

With the above and other objects in view, the invention includes the following novel features and details of construction, combination and arrangement of parts, to be hereinafter more fully described and illustrated in the accompanying drawings.

In the drawings:

Figure 1 is a plan view of a portion of the platen of a Gordon press, showing that portion of the Miller automatic feeding mechanism which is carried by the platen.

Fig. 2 is an edge view of the same.

Fig. 3 is a detail sectional view on the line 3—3 of Fig. 1.

Fig. 4 is a detail perspective view of the invention *per se*.

Fig. 5 is a view of a modified form showing the manner of lengthening the finger.

Referring in detail to the drawings, wherein like characters of reference denote corresponding parts, the numeral 10 designates the platen of a Gordon press, which

is equipped with a Miller automatic press feeder. The portion shown includes a finger holder 11, the arm 12 which actuates the holder to impart a reciprocatory movement thereto, a guide nut 13 which is threaded upon the gripper shaft A and connected to the arm 12 by means of a link a.

The shaft A which carries the grippers 14 for holding the sheet 15 in position to receive the impression, also acts to move the guide nut 13 longitudinally of the platen and through the medium of the arm 12, impart an oscillating movement to the finger holder 11, all of which is of ordinary construction and operations and forms no part of the present invention. The usual gage pins 16 are also shown upon the tympan of the platen 10.

The invention which is adapted to be removably clamped within the finger holder 11 in the usual manner, comprises a flat body member 18, the outer end of which is rounded and beveled to provide a stationary jaw 19, which lies flat upon the platen backing, so that the paper fed thereon will slide over the end of the jaw.

Spaced from the beveled end of the stationary jaw 19, are bearing lugs 20, the latter being formed by bending the material from which the body member is made to provide an offset, which is centrally and transversely slotted for the reception of a movable jaw 21. This last mentioned jaw is provided with an inclined outer end 22, which co-operates with the beveled end of the jaw 21 to provide an entrance for the paper. The jaw 21 is also formed with a reduced shank 23, which is positioned within the slot between the bearing lugs 20, and is provided with a transverse opening for the reception of a pivoted pin 24. The jaw 21 is thus pivotally mounted in a manner to prevent the edge thereof for contact with the flat face of the stationary jaw 19, which acts to reduce friction, so that the softest tissue paper may be fed between the jaws without danger of tearing or buckling. The juncture of the inclined portion 22 and the reduced shank 23 of the jaw 21 forms a gripping shoulder 25, so that while the surface of the jaw 21 which contacts with the paper is small, the said paper is securely held in position to permit of its being fed up to final position against the side gage pin through the pivotal movement of the finger.

105
110

In order to increase the length of the finger, where desired, there is provided an extension 26, which is removably secured to the flat body member 18, through the medium of a sleeve 27.

The invention is susceptible of various changes in its form, proportions and minor details of construction and the right is herein reserved to make such changes as properly fall within the scope of the appended claims.

Having described the invention, what is claimed is:

1. The combination with an automatic feeding mechanism for printing presses having a rotary finger holder, of a finger adapted to be removably secured within said holder and comprising a flat body member having a beveled extremity to provide a stationary jaw, a movable jaw pivotally mounted upon the stationary jaw and comprising a hook shaped member having an inclined outer end cooperating with the beveled end of the stationary jaw to provide an entrance, a reduced shank and a shoulder formed at the juncture of the inclined outer end and the reduced shank for contact with the stationary jaw to provide a grip.
2. The combination with an automatic

feeding mechanism for printing presses having a rotary finger holder, of a finger adapted to be removably secured within said holder and comprising a flat body member having a beveled extremity to provide a stationary jaw, a bifurcated bearing carried by and spaced from the end of the jaw, a movable jaw pivotally mounted within said bearing, an inclined outer end for the movable jaw, said end coöperating with the beveled end of the stationary jaw to provide an entrance, a gripping shoulder on the movable jaw for contact with the stationary jaw and a spring positioned between and secured to the inner end of the movable jaw and the stationary jaw.

3. The combination with an automatic feeding mechanism for printing presses having a rotary finger holder, of a finger adapted to be removably secured within said holder and comprising a flat body member having a beveled extremity to provide a stationary jaw, a spring actuated movable jaw mounted upon the stationary jaw and a lengthening extension detachably connected to the flat body member.

In testimony whereof I affix my signature.

ORLO L. WOOD.
